L. H. ROBINSON

PORTABLE ADJUSTABLE HANGER FOR SHADES, CURTAINS, AND DRAPERIES

Filed April 14, 1925

Lula H. Robinson.
INVENTOR.

Fig. 4.

BY G. Waldrop

ATTORNEY.

UNITED STATES PATENT OFFICE.

LULA H. ROBINSON, OF DALLAS, TEXAS.

PORTABLE ADJUSTABLE HANGER FOR SHADES, CURTAINS, AND DRAPERIES.

Application filed April 14, 1925. Serial No. 23,102.

To all whom it may concern:

Be it known that I, LULA H. ROBINSON, a citizen of the United States, residing at Dallas, in the county of Dallas and State of

5 Texas, have invented certain new and useful Improvements in Portable Adjustable Hangers for Shades, Curtains, and Draperies, of which the following is a specification.

This invention relates to window and door 10 attachments and it refers more particularly to an improvement in adjustable hangers for curtains, shades, draperies and the like, the primary object of which is to provide a 15 convenient hanger having but few parts which function to permit the hanger to be applied to windows and other openings of varying widths and sizes.

The invention further provides a hanger 20 of substantial construction which is provided with separate adjustments for each requirement to conform with the dimensions of an opening upon which it is applied and the body of which is concealed when the curtains and shades are arranged thereon.

25 The invention further contemplates the provision of a hanger constructed in a simple and economical manner, having certain provisions for the vertical adjustment of its position with respect to an opening, from an accessible location to admit suitable ventilation and light into a room from the upper sash of a window, and due to its portable nature, may be readily disassembled and packed into a compact space.

30 The invention has further objects and advantages in its use and construction, which will become more apparent as the description proceeds and which will be set forth and manifested in the course of the following detail description, of which the appended drawings form a part, in which:

35 Figure 1 represents an elevational view of the invention, showing the numerous adjusting features thereof.

40 Figure 2 is a fragmentary view of the end portion, illustrating the hinged feature to permit of adjustment of the retaining slides.

45 Figure 3 is a view of the retaining slides and shade support.

50 Figure 4 is a view of the invention applied, and

55 Figure 5 is a modified form of the shade support.

In proceeding in accordance with the

present invention, 1 denotes the usual telescopic rod, but which is constructed of two channel members arranged to receive an intermediate bar 2, to lend strength to the assembly. These channel members are slotted at *a* to effect restricted longitudinal adjustment of the horizontal positioning of the hanger through members 4—4. The latter members are provided with L-shaped slides 5, arranged to engage beneath the strips 6, disposed upon the sides of the opening 6^a, as shown in Figure 4, to maintain rigidity of the structure. The set screws 7 in the members 4—4 are adjusted to effect the said horizontal positioning of the structure within the opening, at either side thereof, and to facilitate this adjustment, the shade supports 8 are arranged to be hinged at *b*, as shown in Figure 2. This affords a novel means for making such adjustment beneath the support 8 if so desired or required.

60 The spaced depressions in the strips 6, receiving the clips 9^a, afford a means for sustaining the structure at any position along the vertical plane of an opening, such positioning being accomplished by manipulating the depending arms 10 (see Figure 3) which are secured to or from a part of the slides 5. These arms extend downwardly behind the strips 6 and are provided with a suitable purchase 11, having an overturned lug 12 embracing the strip 6 to maintain rigidity.

65 The invention further contemplates the provision of a hanger constructed in a simple and economical manner, having certain provisions for the vertical adjustment of its position with respect to an opening, from an accessible location to admit suitable ventilation and light into a room from the upper sash of a window, and due to its portable nature, may be readily disassembled and packed into a compact space.

70 The invention has further objects and advantages in its use and construction, which will become more apparent as the description proceeds and which will be set forth and manifested in the course of the following detail description, of which the appended drawings form a part, in which:

75 Figure 1 represents an elevational view of the invention, showing the numerous adjusting features thereof.

80 The invention further contemplates the provision of a hanger constructed in a simple and economical manner, having certain provisions for the vertical adjustment of its position with respect to an opening, from an accessible location to admit suitable ventilation and light into a room from the upper sash of a window, and due to its portable nature, may be readily disassembled and packed into a compact space.

85 Figure 2 is a fragmentary view of the end portion, illustrating the hinged feature to permit of adjustment of the retaining slides.

90 Figure 3 is a view of the retaining slides and shade support.

95 Figure 4 is a view of the invention applied, and

100 Figure 5 is a modified form of the shade support.

105 In proceeding in accordance with the

110 invention has been disclosed as embodying the structure set forth in the appended claims and it is not desired that the same be limited to the specific showing herein, also that minor changes and modifica-

tions as to form and application may be made as fall within the meaning and scope of the claims hereto.

What is claimed is:

- 5 1. In a shade hanger and the like, a horizontal support, end members on and adjustable lengthwise of the end parts of the support, slides carried by the members, strips formed for vertical rigid securing to a window frame and engageable with the slides, shade supports hinged to the ends of the horizontal support whereby upon outward movement thereof to permit of adjustment of the end members relative to the shade supports, said strips having notched edges, clips carried by the slides and selectively engageable in the notches of the strips,

a rod connected to each clip and engaging the corresponding strip, and holding means for the lower ends of the rods engaging the strips.

2. In a shade hanger and the like, a horizontal support, end members on and adjustable lengthwise of the end parts of the support, slides carried by the members, strips formed for vertical rigid securing to a window frame and engageable with the slides, and shade supports hinged to the ends of the horizontal support whereby upon outward movement thereof to permit of adjustment of the end members relative to the shade supports.

In testimony whereof I affix my signature.

LULA H. ROBINSON.
